IRON CORD SUPPORT

Andrew G. Ten Eyck, Detroit, Mich.

Application October 22, 1945, Serial No. 623,732

4 Claims. (Cl. 248—51)

1

This invention relates to electric iron cord supports or holders and particularly to a device attachable to an ironing board, table or the like and having means for supporting the flexible cord of an electric iron above the ironing surface so as not to interfere with the operation of the iron.

An object of the invention is to provide an improved holder or support for the flexible cord of an electric iron which is of relatively simple, light and inexpensive construction, efficient and practicable in use and adapted to be mounted on the ironing board or table at any convenient location along the side or at the end thereof.

A further object of the invention is to provide an improved supporting device for an electric iron conductor cord embodying an upright swinging standard carrying at its upper end an inextensible, flexible cord, string or the like of suitable length attachable at its end to the conductor cord, said standard being pivotally mounted at its lower end so as to swing to and fro against the action of a spring in response to motion imparted to the inextensible cord during the ironing operation.

Another object of the invention is to provide a yieldable support or carrier for an electric iron conductor cord effective to hold the cord above the ironing surface free of interference with the iron and in which the improved construction is such that a minimum of resistance is imposed on the operator in manipulating the iron, provision being made for varying the effective effort of the yieldable supporting means so as to substantially counterbalance the weight of the iron cord.

Other objects of this invention will appear in the following description and appended claims, reference being had to the accompanying drawings forming a part of this specification wherein like reference characters designate corresponding parts in the several views.

Fig. 1 is a side elevation illustrating an electric iron cord support or holder embodying the present invention and mounted in operative position upon an ironing board.

Fig. 2 is an enlarged side elevation, partly broken away, illustrating the holder shown in Fig. 1.

Fig. 3 is a plan view, partly in section, taken substantially through lines 3—3 of Fig. 2 looking in the direction of the arrows.

Fig. 4 is a fragmentary section taken substantially through lines 4—4 of Fig. 3 looking in the direction of the arrows.

Before explaining in detail the present inven-

2

tion it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

The iron cord support or holder of the present invention is adapted to be mounted upon any suitable support having an ironing surface and in the present instance is illustrated as mounted at one end of a conventional ironing board 10 having the usual folding supporting legs 11. The cord support or holder, embodying the present invention and illustrated by way of example in the drawings, comprises a base or supporting block 12 formed of suitable material. In the present instance the base 12 is molded from plastic material and formed at its front side with a longitudinal slot or opening 13 into which extends the lower end of an upright standard or rod 14 which is also preferably formed of plastic material. The lower end of the standard 14 is pivoted within the slot 13 by means of a transverse pin 15, thus permitting the standard to swing to and fro in a vertical plane. The guide slot 13 for the standard 14 has a width corresponding substantially to the diameter of the standard 14 so as to permit the latter to swing between the parallel edges 13a of the guide slot while at the same time holding and bracing the standard against lateral tilting movement. The material of the base 12 is under-cut at 16 at the rear of the guide slot 13 so as to provide a recess into which the lower terminal end of the standard 14 may project when the standard is swung down to a horizontal position for storage when not in use. When thus positioned horizontally, as shown in dotted lines in Fig. 4, the lower end of the standard or rod 14 will engage the overhanging wall 16a of the under-cut recess 16 and at the same time the rod will pass between a pair of embossments 17 which will spread apart sufficiently to permit passage of the rod 14 therebetween. These embossments 17 will thus yieldingly hold the rod or standard in its horizontal position.

Swinging motion of the rod or standard 14, such as from the full line to the dotted line position of Fig. 2, is resisted by means of a light tension spring 18 having its lower end 18a hooked beneath and anchored to a projecting lug 19 and having its upper hooked end 18b anchored in

any one of a series of vertically spaced notches 20 cut in the front side of the standard or rod 14. It will be apparent from this construction that the degree of resistance exerted by the spring 18 to the forward swinging motion of the standard 14 may be varied and regulated by varying the height of the connection of the end 18b of the spring with the standard 14, this being accomplished by moving the hooked end of the spring from one notch 20 to another. Thus, the higher the point of connection of the end 18b of the spring with the rod 14 the greater will be the resistance exerted by the spring.

Loosely attached to the upper end of the rod or standard 14 is an inextensible cord or string 21 of suitable length, the upper end of the string being passed through a hole or eye 22 in the standard and knotted at its end so as to prevent withdrawal of the cord when a longitudinal pull is exerted thereon. After the holder has been mounted in suitable position upon the ironing board 10, as illustrated in Fig. 1, the lower end of the string or cord 21 may be looped around and slidingly attached to the electric cord or conductor 23 of an electric iron 24, this conductor cord at its end being plugged into a socket 25 in the usual manner. For the purpose of releasably clamping the base 12 to the edge of the ironing board 10, either along the side or end thereof, a clamping plate 26 is secured in underlying position to the base 12 as by means of screws 27. This plate is of general U-shape having a depending end portion 28 terminating at its lower end in a forwardly bent spring clamping member 29. From this construction it will be seen that the spring clamp may be forced over the edge of the ironing board to yieldingly grip the same and firmly hold the base 12 in the desired position.

It is important to note that by virtue of the present invention the iron cord will be supported above the ironing surface out of the path of the iron in all ironing positions thereof. Furthermore, by suspending the iron cord from the top of the carrier rod or standard through the medium of the string or cord 21 no appreciable resistance is at any time imposed on the operator and, hence, no more effort is required to operate the iron than would normally be required if the present device were not employed. A very light resistance spring may also be used and may be adjusted to the correct position in the height of the standard so that the leverage exerted thereon by the standard will substantially counterbalance the weight of the iron cord. It is also important to note that the iron cord during use of the iron is not subject to friction, bending or twisting at any point in its length and, hence, no wear on the cord results from the use of the present holder. By suspending the iron cord from the end of the string 21 it is possible to utilize a standard of minimum height, since the standard or carrier rod need swing through only a portion of the arc which would otherwise be necessary if the iron cord were connected directly to the upper end of the standard. The present device also has the advantage of being useful in supporting an iron cord of standard length regardless of whether the iron is used with a cord attached at its end by a base plug or a wall plug or is used with a drop cord.

I claim:

1. An iron cord support comprising a base, a standard having its lower end extending within

a slot in the base and pivoted thereto within the slot, said standard being guided for swinging motion in one direction by the parallel sides of said slot, a tension spring connected at one end to the base and adapted to be adjustably connected at its opposite end to the standard for yieldingly holding the standard in upright position, and a length of cord or string depending from the upper end of the standard and attachable to an iron cord for suspending the same over an ironing board at a distance below the upper end of the standard.

2. An iron cord support comprising a base, a standard having its lower end extending within a slot in the base and pivoted thereto within the slot, said standard being guided for swinging motion in one direction by the parallel sides of said slot, a tension spring connected at one end to the base and selectively connectable at its opposite end in any one of a plurality of spaced notches in the side of said standard, and a length of cord or string depending from the upper end of the standard for suspending an iron cord therefrom and effective to support the iron cord over an ironing board a substantial distance below the upper end of said standard.

3. An iron cord support comprising a base, a standard having its lower end extending within a slot in the base and pivoted thereto within the slot, said standard being guided for swinging motion in one direction by the parallel sides of said slot, a tension spring connected at one end to the base and adapted to be adjustably connected at its opposite end to the standard for yieldingly holding the standard in upright position, and a length of cord or string depending from the upper end of the standard and attachable to an iron cord for suspending the same over an ironing board at a distance below the upper end of the standard, said slot being open at one end and said standard being swingable into horizontal position within said slot.

4. An iron cord support comprising a base, a standard having its lower end extending within a slot in the base and pivoted thereto within the slot, said standard being guided for swinging motion in one direction by the parallel sides of said slot, a tension spring connected at one end to the base and adapted to be adjustably connected at its opposite end to the standard for yieldingly holding the standard in upright position, a length of cord or string depending from the upper end of the standard and attachable to an iron cord for suspending the same over an ironing board at a distance below the upper end of the standard, said slot being open at one end and said standard being swingable into horizontal position within said slot, and means on the base for holding the standard in said horizontal position.
